A. C. LIPPERT

AUTOMOBILE RADIATOR CAP

Filed Nov. 3, 1924

Patented July 28, 1925.

1,547,177

UNITED STATES PATENT OFFICE.

ALOYSIUS C. LIPPERT, OF KENOSHA, WISCONSIN, ASSIGNOR OF ONE-HALF TO C. A. NORTON, OF CHICAGO, ILLINOIS.

AUTOMOBILE RADIATOR CAP.

Application filed November 3, 1924. Serial No. 747,432.

To all whom it may concern:

Be it known that I, ALOYSIUS C. LIPPERT, a citizen of the United States, residing in Kenosha, in the county of Kenosha and 5 State of Wisconsin, have invented a new and useful Improvement in Automobile Radiator Caps, of which the following is a specification.

The present invention relates to closures 10 for automobile radiators and the like, and has for a principal object the provision of a radiator cap having the general advantages described and claimed in copending application Serial No. 747,434, of Aloysius 15 C. Lippert and Anthony H. Hackl, and in addition thereto having provisions for attachment to the radiator neck which facilitate adaptation of the cap to radiator necks of different size.

20 A further object of the invention is the provision of a radiator cap of the general type of the copending application above referred to, provided with sealing means which may, perhaps, be preferred to that 25 shown in said co-pending application and which sealing means, as well as the remainder of the construction, may be inexpensively provided so that the cap may be placed upon the market at relatively low 30 cost.

Numerous other objects and advantages of the invention will be apparent as it is better understood from the following description, which, taken in connection with 35 the accompanying drawings, discloses a preferred embodiment thereof.

Referring to the drawings,

Figure 1 is a front elevation of a radiator cap in which the invention is embodied, the 40 same being shown in position upon the filler neck of a radiator and being partially broken away and sectionalized for convenience in illustration; and

Figs. 2 and 3 are horizontal sectional 45 views, taken respectively upon the section lines 2-2 and 3-3 of Fig. 1.

In said drawings, I have shown, for illustrative purposes only, a preferred form of my invention, in which the reference 50 character 11 indicates an outer body, having laterally extending arms 12 and being provided with a hinged cover 13, adapted to carry a motometer 14, or like device, a latch 55 being provided to hold said cover tightly to the body and in contact with a gasket 16,

of rubber or like material, suitably positioned upon the interior of said body. An inserted locking member 17, of brass or like workable material, is disposed in a central opening 18 in said body and in the present 60 instance is adapted to be locked to said body by means of integral projections 19, extending into a circular groove 21 formed on the interior of the cap body, it being apparent that with this construction, said body 65 may be rotated relatively to the insert, but separation of the parts is prevented and the rotation of the body will not tend to remove said insert from the radiator neck. Said insert 17, at the lower end thereof, is 70 bent back upon itself, as indicated at 22 and the inner, upwardly extending portion 23 thus provided is threaded, as indicated at 24, and adapted to screw upon the radiator neck 25. The upper extremity of the portion 23 of said insert is bent slightly outwardly, as shown at 26, and then inwardly and downwardly to provide an edge portion 27 adapted to tightly contact with the 75 top of said radiator neck when the insert is screwed down to the position shown in Fig. 1. It will be manifest that the diameter of the threaded portion 23 of the insert may be varied in accordance with the 80 manner in which said portion is bent from 85 the body of said insert, thereby to accommodate radiator necks of different size, the diameter of the body of the insert being the same for all sizes and the threaded portions being disposed at any desired distance from 90 said body, in manner which will be readily understood. Thus the inserts may be provided for attachment to the varying sizes of radiator necks by merely disposing the 95 threaded portions 23 thereof at different distances from the body, the remaining operations and the construction and sizes of the other parts being the same for all radiators.

For the purpose of screwing the cap onto the radiator, I employ a ratchet member 100 28, disposed in a recess 29 in the insert and having a projecting edge part 31 adapted to engage in recesses 32 formed in the outer cap body and engageable when said outer body is rotated in one direction only. One 105 of the recesses 32 extends to the bottom of the outer body, as shown in Fig. 1, to facilitate the assembly of the body and insert with the ratchet member 28 in position, and it will be understood that the number of 110

ratchets and of said recesses might be increased, if desired. I prefer, however, to provide said recesses at opposite sides of the cap, inwardly from the projecting arms 12, as shown in the drawings, since there is more stock in this area and the grooves are less likely to weaken the cap body.

It is thought that the invention and many of its attendant advantages will be understood from the foregoing description, and it will be apparent that various changes may be made in the form, construction and arrangement of the parts without departing from the spirit and scope of the invention, or sacrificing all of its material advantages, the form hereinbefore described being merely a preferred embodiment thereof.

I claim:

1. A radiator cap for automobiles or the like, comprising an outer body, and an inserted locking member secured thereto and permitting relative rotation of the outer body, the lower end of said inserted member being bent inwardly within the body portion thereof and threaded for attachment to the radiator neck.

2. A radiator cap for automobiles or the like, comprising an outer body, and an inserted locking member secured thereto and permitting relative rotation of the outer body, the lower end of said inserted member being bent inwardly within the body portion thereof and threaded for attachment to the radiator neck, and having a part beyond the threads adapted for sealing engagement with the top of said neck.

3. A radiator cap for automobiles or the like, comprising an outer body, a closure pivoted to said body, and an inserted locking member secured thereto and permitting relative rotation of the outer body, the lower end of said inserted member being bent inwardly within the body portion thereof and threaded for attachment to the radiator neck.

4. A radiator cap for automobiles or the like, comprising an outer body, a closure pivoted to said body, and an inserted locking member secured thereto and permitting relative rotation of the outer body, the

lower end of said inserted member being bent inwardly within the body portion thereof and threaded for attachment to the radiator neck, and having a part beyond the threads adapted for sealing engagement with the top of said neck.

5. A radiator cap for automobiles or the like, comprising an outer body, and an inserted locking member formed of bendable material and having a vertical wall and a portion bent upwardly within said wall and provided with means for attachment to the radiator neck.

6. A radiator cap for automobiles or the like, comprising an outer body having an opening therein, and a locking member disposed within said opening and having throughout a part of its height a double wall, one part of which is provided with means for attachment to the radiator neck.

7. A radiator cap for automobiles or the like, comprising an outer body having an opening therein, and a locking member disposed within said opening and having an attaching portion arrangeable at varying distances from the body part thereof, said attaching portion having an extension engageable with the top of the radiator neck to prevent leakage.

8. A radiator cap for automobiles or the like, comprising an outer body having an opening therein, and an inserted locking member having a double wall, one part of which is provided with means for attachment to radiator necks of different diameter without change of form of the body portion of said member.

9. A radiator cap for automobiles or the like, comprising an outer body having an opening therein, and a locking member disposed within said opening and having an attaching portion arrangeable at varying distances from the body part thereof, said locking member having an end flange engageable with the top of the radiator neck to prevent leakage and said flange being rolled to provide clearance about the outer edge of the radiator neck and to stiffen the flange.

ALOYSIUS C. LIPPERT.
